CLAIM

The ornamental design for a rake cart or the like, as shown and described.

DESCRIPTION

FIG. 1 is a top plan view of a rake cart showing my new design, and showing finger wheel rakes and a tractor in dashed lines for illustrative purposes only;

FIG. 2 is a top plan view thereof;

FIG. 3 is a side elevational view thereof, the opposite side being a mirror image of the side shown;

FIG. 4 is a front view thereof;

FIG. 5 is a rear view thereof having a portion of each tire broken away; and,

FIG. 6 is a perspective view thereof.
